TELEGRAPH SYSTEM

John L. Callahan, Brooklyn, N. Y., and Richard E. Mathes, Westfield, N. J., assignors to Radio Corporation of America, a corporation of Delaware

Application February 25, 1933, Serial No. 658,582

7 Claims. (Cl. 178—17.5)

This invention relates to synchronous multiplex systems and particularly concerns a method of and means for inter-linking start-stop printer apparatus with one or more channels of a multiplex system.

In setting up start-stop printer apparatus for multiplex use, it is customary to control the rotating mechanism at the printer station by means of a cadence pulse generated by the multiplex equipment, or to have the cycles of operation of the start-stop apparatus controlled by the multiplex distributor. Several such arrangements are described in the book entitled "Printing Telegraph Systems and Mechanisms" by H. H. Harrison published in London, 1923, particularly pages 413 to 415, to which reference is made for a more detailed description of present day general practice.

The present invention has for its object to provide a system which enables the cycles of operation of the start-stop printer apparatus to function independently of the multiplex equipment control, and this is accomplished, briefly, by first storing the start-stop printer impulses as they occur in normal operation, in order to overcome irregularities in the operation of the printer equipment, and then retransmitting the pulses at a synchronous rate into the synchronous multiplex system. The storage device for the signals, which may be either electrical, mechanical or chemical, absorbs the irregularities of operation normally experienced in the start-stop communication systems.

One advantage of this invention is that it overcomes the need for definite control of the start-stop printer equipment by the multiplex equipment, or for observing a certain speed of printer operation on the part of the operator.

In the accompanying drawings, Figure 1 illustrates, diagrammatically, a circuit partly electrical and partly mechanical of a preferred form of the present invention, and Figure 2 illustrates, schematically, another embodiment thereof.

Referring to Figure 1 in more detail, there is shown a line relay 20 for receiving over transmission line 22 the signal characters from the distant transmitting printer equipment. The tongue of relay 20 is arranged to be normally on its positive contact when the transmitting printer is in the stop position. The printer may be of any desired type, although it is preferred to use the well known Teletype of Kleinschmidt apparatus for sending different combinations of signal characters. These signal characters may consist of any two different kinds of electrical

conditions, such as permutations of positive and negative impulses, or current and no current extending through a definite number, usually five time intervals or units in addition to a start and a stop pulse.

A motor 25 is provided for driving the multiplex transmitting machine, not shown, over main driving shaft 26 which, in turn, is arranged to drive shafts 23 and 24 which are individual to the receiving and transmitting contact set assemblies, respectively, through a suitable worm gear combination 27, the latter providing a gear ratio such that shaft 23 operates at about seven per cent greater speed than the nominal speed of the start-stop printer, and shaft 24 operates at such speed that the multiplex distributor, not shown, assigns the circuit to the storage output seven times for one revolution of shaft 24.

The receiving and transmitting contact set assemblies 40 and 41 are connected to their respective driving shafts 23 and 24 through shafts 30 and 31 and clutches 28 and 29, respectively. Shafts 30 and 31 are normally prevented from rotating by clutch releasing detents 32 and 33 which are adapted to engage cams on the shaft 25 in a manner well known in the art. These detents constitute armatures of relays 34 and 35, respectively, which, when operated, release the shafts 30 and 31 and permit their movement for only one revolution before they again engage the cams on the shaft to prevent further movement thereof. The clutches may be of any desired cam controlled type comprising a clutch driving member such as shafts 23 and 24 and a clutch driven member such as shafts 30 and 31. It is preferred, however, to use the slip friction type of clutch.

Cam contact set assemblies 40 and 41 comprise arrangements well known in the printer field, particularly in connection with teletype machines, whereby when the cam shafts 30 and 31 rotate, the contacts 1, 2, 3, 4, etc. and 1', 2', 3', etc., respectively, close successively due to motion of setting levers of the goose-neck type, not shown, which enter depressions on a common cylindrical, rotary cam, not shown. One manner of mounting these levers on a common cam is described in detail in United States Patent 1,595,472, granted August 10, 1926 to H. L. Krum, to which reference is made only by way of example.

Receiving cam contact assemblage 40 is so arranged that when the rotary cam is in the stop position, as indicated in the drawings, all contacts except special contact 1 are open.

A multiplex synchronizing cam 18 is provided either on the same shaft with the multiplex com-

mutator or distributor, not shown, or on some other shaft definitely geared thereto, and is arranged to cause a contact 19 to make once for each channel Baud, i. e., each signalling unit of 5 the stored start-stop printer channel. This contact 19 is so phased that detent release magnet 35 will operate and permit transmitting cam shaft 31 to rotate to approximately the center of the closure of contact 1' before the multiplex distributor assigns the multiplex circuit to the start-stop printer channel.

The only limitation necessary to be imposed upon the start-stop printer is that the speed of its transmitting cam shaft be not greater than 15 the channel speed of the multiplex system. There is, of course, also a minimum speed of this shaft, but the normal operation of start-stop printers which maintains the speed to within about 8% of the nominal assigned speed will suffice to meet 20 the requirements of this storage system.

The operation of the circuit of Figure 1 is as follows:

Upon the receipt of the first unit of the code group transmitted by the distant start-stop printer apparatus, the tongue of relay 20 will be 25 pulled over to the negative contact, thus completing a circuit through release detent magnet 34, current limiting resistance 36, receiving cam drum contact 1 to positive potential. It should 30 here be noted that contact 1 is closed by the receiving cam drum after the latter has completed one revolution and until the start of the next revolution. The energization of detent magnet 34 attracts detent arm 32 and permits the cam 35 drum of receiving contact set assemblage 40 to rotate, thus opening contact 1 and momentarily closing contacts 2 to 7 inclusive in succession, then again closing contact 1 in preparation for the next start pulse. After one revolution the 40 detent arm 32 will again engage shaft 30 and stop the cam drum. In this manner there is obtained one revolution per character code group. The closure of the receiving contacts 2 to 6 inclusive, in succession, enables the respective condensers 45 C₂ to C₆ inclusive to acquire a positive or negative charge over an obvious circuit as determined by the incoming signal units which act to place the tongue of relay 20 on either the positive or negative contact. Contact 7 operated by the receiving cam is herein not used.

The positive center terminal of contact 1 is arranged to close with its right hand contact immediately after the receiving cam drum of assemblage 40 starts to rotate and just before contact 2 is closed. This closure prepares a circuit 55 from the positive terminal of contact 1 to contact 19, the latter being under the control of the multiplex synchronizing cam 18. Multiplex synchronizing cam 18 operates in the manner described above in order to provide for assigning the multiplex circuit to the start-stop printer channel, the closure of contact 19 by this cam enabling the energization of release detent magnet 35 which, in turn, permits the transmitting cam shaft 31 60 to rotate for a single revolution, causing contacts 1' to 7' inclusive, of transmitting contact set assemblage 41 to close in succession. In closing, contact 1' impresses a negative pulse analogous to the start signal pulse, onto the multiplex input circuit indicated in the drawings by lead 37. The continued rotation of transmitting cam shaft 31 65 for one revolution causes contacts 2' to 6' to close successively and thereby discharge the respective condensers C₂ to C₆ inclusive, over an obvious circuit into the multiplex input circuit 37, when and

as directed by the successive assignments of the multiplex circuit, to the start-stop printer channel. The closure of contact 1' impresses a positive or stop pulse on the multiplex input circuit, after which the transmitting cam shaft 31 is 5 stopped by action of the detent 33. During idle periods of the storage device, transmitting contact 1' is normally arranged to engage the cam whereby positive pulses are continuously transmitted out over the multiplex equipment at the intervals 10 assigned to the channel.

In Figure 2 is shown an alternative arrangement comprising, essentially, two distributor faces whose corresponding segments are respectively directly connected together, one face being adapted to store the signals received from the printer equipment and the other to repeat the stored signals into the multiplex equipment. Individual brush arms X and Y are provided for each face. These arms are mounted on a common shaft and connected thereto by friction clutches, not shown, which are controlled by respective release detent magnets 50 and 51 having detent armatures G and H respectively engaging dogs on the shaft. A motor 53 which drives the 20 main multiplex driving shaft supplies the power for rotating the common shaft through a suitable gear reduction arrangement, not shown.

The storage face is designed to have a main ring of seven short segments 1 to 7 inclusive, each 30 of which is connected to a storage condenser C₁ to C₇ for storing the printer impulses. Brush arm X makes one revolution for each character group of unit impulses received from the start-stop printer apparatus over transmission line 22 and through line relay 20. Detent armature H will normally engage a dog 54 fastened to brush arm X once each revolution and will thus stop arm X at the position shown in the drawings. This arm is provided with two brushes M and N which are 40 directly connected together, the former resting on an auxiliary segment A and the latter on an auxiliary segment B of an inner ring.

The repeating face, except for the longer segments and the absence of auxiliary segmental contacts, is arranged in a similar manner to the storing face. On this face, brush arm Y is provided with only a single brush P which makes, together with the arm, one revolution for each full seven unit signal character to be transmitted 55 by the multiplex channel. These seven units comprise, of course, the usual five unit printer signal combination in addition to the start and stop pulses. The segments of this repeating face are connected to similarly numbered segments on the storing face. Detent armature G, it should be noted, is normally open. When brush arm X, however, is in the position shown, a circuit is completed which is traced from positive potential on the upper contact and armature of relay 60 20 through brushes M and N, segment B, and detent release magnet 50 to ground, to operate detent release magnet 50 and attract detent arm G, so that brush arm Y will be stopped when it has advanced to the position shown in the drawings. 65 As detent arm G is attracted by its magnet, a locking circuit for the release magnet 50 is closed through the auxiliary contacts E and F and the tongue of line relay 20 in an obvious manner.

From the foregoing it will readily appear that 70 the arrangement of Figure 2 can be designed so as to store only five signalling units, as is done in the preferred arrangement of Figure 1, and the start and stop units can be provided from a local source of energy.

It should here be noted that although the storing and repeating faces appear in Figure 2 of the drawings to face the same direction, actually, in the device used they are placed back to back. 5 This is done in the actual construction in order to simplify the connections between corresponding segments of the two faces and for maintenance purposes.

In the operation of the circuit of Figure 2, the receipt of a separate pulse from the start-stop apparatus through relay 20 causes the armature of this relay to move to its negative contact, thus closing a circuit from negative potential on the relay contact, brush M, segment A, winding of 5 detent release magnet 51 to positive potential, actuating magnet 51 which, in turn, attracts detent armature H, releasing dog 54 and permitting brush arm X to make one complete revolution. During the course of this revolution positive and negative charges are placed upon the successive condensers in the storage condenser group C₁ to C₇ inclusive, depending upon the position of the tongue of relay 20 as determined by the successive character unit impulses sent out 10 from the start-stop apparatus. The character impulses will be stored by the condensers in the condenser storage group until such time as they may be advantageously used by the multiplex channel upon its assignment to the start-stop 15 printer apparatus.

Brush arm Y on the repeating face is held stationary through slightly more than one unit of time by virtue of the length of segment B of the storing face which aids in maintaining magnet 50 in its operated position over a circuit previously described. As brush arm X passes on towards number 2 segment this circuit will be opened and detent release magnet 50 will be held in its operated position only by virtue of the self-locking circuit over contacts E and F, mentioned above. This circuit remains closed until contact F is opened by a cam 40 which is directly connected to the shaft driven by motor 53. This cam is so positioned that it will open 20 contact F just slightly before the multiplex distributor assigns the circuit to the start-stop printer channel. As contact F opens, detent G is released and brush arm Y starts to revolve. Brush arm Y, carries brush P which, in turn, is coupled to the multiplex distributor equipment, and is arranged as it revolves to discharge successive condensers in the storage condenser group in the proper order and at the proper time when and as the multiplex circuit is assigned to the 25 printer channel.

It is thus apparent that the repeating face functions to send out impulses to the multiplex equipment one to two units of time behind the receipt of these impulses by the storing face. If brush arm X of the storing face is stopped, however, for any length of time by its detent H, brush arm Y will continue its rotation until it catches up to brush arm X, but will not stop until the complete seven unit character, comprising five message units in addition to the start and stop pulses, has been sent through the multiplex channel. Brush P carried by brush arm Y is arranged when not in motion to rest on an inactive portion of the ring, and for this reason the space between segments 1' and 7' is made slightly longer than that between the other segments. 30

It is to be understood, of course, that the invention is not limited in scope to the precise arrangements shown, since different kinds of start-stop printers, such as stock tickers, may be 35

used, and various modifications may be made either in the electrical circuits or in the type of storing device, which may be of any suitable kind, without departing from the spirit and scope of the present invention. 5

We claim:

1. In combination, a plurality of signal storing elements, an input circuit for receiving signals and supplying positive and negative potential charges to said elements in accordance with said received signals, circuit closing members operative in succession for successively connecting said input circuit to different ones of said storing elements, other circuit closing members connected to said signal storing elements, and start-stop means under control of a utilization circuit for causing said storing elements to be successively connected through said last circuit closing members to said utilization circuit. 10

2. A multiplex telegraph system employing start-stop printer apparatus having, in combination at a single central station, an electromagnetic relay having an armature and two contacts of opposite polarity adapted to alternately engage with said armature, said relay being responsive to signals from said printer apparatus, a plurality of storing condensers, start-stop mechanism, circuit closing members operative in succession and in circuit with the armature of said relay for applying charges from the contacts 15 of said relay to said condensers in accordance with the received signals, said members being under control of said start-stop mechanism, other similar circuit closing members individually connected to said storing condensers for discharging said condensers into multiplex equipment, start-stop mechanism for said last circuit closing members, said last start-stop mechanism being under control of said multiplex equipment. 20

3. A multiplex telegraph system employing start-stop printer apparatus having, in combination at a single central station, a set of receiving and a set of transmitting contacts, start-stop mechanisms individual to said sets of receiving and transmitting contacts and operable to close 25 the individual contacts of the respective sets in succession, a plurality of signal storing elements each of which is connected in common to corresponding contacts of said receiving and transmitting sets, a line connecting said station to distant printer apparatus, a relay at said station responsive to signals received over said line for releasing the start-stop mechanism associated with said set of receiving contacts and for impressing signals upon said storing elements 30 through said receiving contacts, multiplex equipment, and a cam arrangement under control of said multiplex equipment for causing the release of the start-stop mechanism associated with said set of transmitting contacts, said set of transmitting contacts being arranged to discharge 35 said signal storing elements into said multiplex equipment. 40

4. A multiplex telegraph system employing start-stop printer apparatus having, in combination at a single central station, a set of receiving and a set of transmitting contacts, start-stop mechanisms individual to said sets of receiving and transmitting contacts and operable to close 45 the individual contacts of the respective sets in succession, a plurality of signal storing elements each of which is connected in common to corresponding contacts of said receiving and transmitting sets, a line connecting said station to distant 50 printer apparatus, a relay at said station responsive to signals received over said line for releasing the start-stop mechanism associated with said set of transmitting contacts, said set of transmitting contacts being arranged to discharge 55 said signal storing elements into said multiplex equipment. 60

sive to signals received over said line for releasing the start-stop mechanism associated with said set of receiving contacts and for impressing signals upon said storing elements through said 5 receiving contacts, multiplex equipment, and means under control of said multiplex equipment for causing the release of the start-stop mechanism associated with said set of transmitting contacts, said set of transmitting contacts 10 being arranged to discharge said signal storing elements into said multiplex equipment.

5. A multiplex telegraph system employing start-stop transmitting printer apparatus having, in combination, an electromagnetic relay having, 15 an armature and two contacts of opposite polarity adapted to be alternately engaged by said armature, said relay being responsive to signals from said printer apparatus, a plurality of storing condensers, circuit closing members operative in succession and in circuit with the armature of said relay for applying charges from the contacts of said relay in accordance with the received signals upon said condensers, other similar circuit closing members individually and directly connected to said storing condensers for discharging said condensers, and means under control of multiplex equipment for successively connecting electrically the multiplex equipment 20 with said other circuit closing members.

25 6. A multiplex telegraph system employing start-stop transmitting printer apparatus having, in combination, an electromagnetic relay having an armature and two contacts of opposite polarity adapted to be engaged by said armature, said

relay being responsive to signals from said printer apparatus, a plurality of storing condensers, circuit closing members connected to said condensers, means coupled to said armature and arranged to engage said members successively for applying charges from the contacts of said relay to said condensers in accordance with the received signals, said means being made operative upon receipt of a start impulse from said printer apparatus to said relay, other circuit closing members 10 in parallel relationship with said first circuit closing members, and means connected to and under control of the multiplex equipment for successively connecting electrically said multiplex equipment with said other circuit closing members. 15

7. In an apparatus for a multiplex system adapted to receive start-stop signals employing a definite interval code, sets of receiving and transmitting contacts, corresponding sets of start-stop mechanisms operable to close the individual contacts of their respective sets in succession, a plurality of signal storing elements, each of which is directly connected to corresponding contacts of said receiving and transmitting sets, a relay responsive to the start-stop signals 20 for starting said receiving mechanism and for impressing signals upon said storing elements, and another relay under the control of the multiplex equipment for starting said transmitting mechanism to discharge the signals stored on said elements into said multiplex equipment. 25
